UNITED STATES PATENT OFFICE.

BENJAMIN S. SAMUELS, OF NEW YORK, N. Y.

DESIGN FOR A PAPER-WEIGHT OR OTHER ORNAMENT OF SIMILAR NATURE.

53,183.

Specification for Design.

Patented Apr. 8, 1919.

Application filed June 3, 1918. Serial No. 238,060. Term of patent 3½ years.

To all whom it may concern:

Be it known that I, BENJAMIN S. SAMUELS, a citizen of the United States, residing in the city, county, and State of New York, have invented a new, original, and ornamental Design for a Paper-Weight or other Ornament of Similar Nature, of which the following is a specification, reference being had to the accompanying drawing, forming part thereof.

Figures 1 and 2 are elevations respectively of opposite sides of a paper weight, or other ornament of similar nature showing my new design.

I claim:—

The ornamental design for a paper weight, or other ornament of similar nature, as shown.

BENJAMIN S. SAMUELS.
